JAMES TIBURCE FELIX CONTI, OF PARIS, FRANCE, ASSIGNOR TO SOCIÉTÉ INDUSTRIELLE D'INSTRUMENTS DE PRÉCISION, OF PARIS, FRANCE.

SUSPENSION FOR BALANCE PLATES.

1,424,239.

Specification of Letters Patent. Patented Aug. 1, 1922.

Application filed June 5, 1920. Serial No. 386,772.

To all whom it may concern:

Be it known that I, JAMES TIBURCE FELIX CONTI, of Paris, France, a citizen of the French Republic, have invented Suspensions for Balance Plates, of which the following is a full, clear, and exact description.

It is known that balances which are provided with platform plates, that is to say not suspended by wires or chains, necessitate a multiplicity of knife-edges and of four-bar motions combined in such a manner as to obtain a constant indication of weight, whatever may be the point of the plate where bears the load.

15 This invention relates to an extremely simple arrangement which may be advantageously applied on any balances in which the amplitude of vertical oscillation of the plate is very reduced. This arrangement, 20 by suitably limiting the strokes of the suspension knife-edges, may be applied to any balances, but it is more particularly convenient for Conti and Roman balances in which a vertical displacement nearly nil can 25 be given to the knife-edge supporting the load.

The invention consists, substantially, in mounting the plate on two vertical members, resting on one another and capable of moving vertically according to a very small extent, but the inclination of which to the vertical is rendered impossible by means of flexible and inextensible wires stretched horizontally.

35 By means of this device, it is possible to do entirely away with the lateral pressures of the suspension knife-edge, whatever may be the point of application of the load on the plate.

40 Various methods of carrying out the invention are diagrammatically illustrated, by way of example only, in the accompanying drawing, in which:

45 Figures 1 and 2 illustrate in elevation and plan view respectively a Roman balance provided with the suspension device forming the subject-matter of the invention.

Figure 3 shows this device applied to a Conti balance and

50 Figures 4 and 5 illustrate the application of the device to an ordinary balance with two plates.

Referring to the drawing, it will be seen, in the example illustrated in Figs. 1 and 2,

that the plate *a* of the Roman balance is 55 integral with a tube *b*.

This tube *b* is held vertically by means of two horizontal cross pieces each constituted by four flexible and inextensible wires or small chains *c* arranged crosswise, one of 60 these cross pieces being located immediately underneath the plate *a* and the other at the lower part of the tube *b*. The ends of each of the flexible wires *c* are attached on the one hand to the tube *b* and on the other hand 65 to stretching devices *d* suitably carried by supporting columns *d*¹.

The tension of the various flexible elements *c* forming the two cross pieces is adjusted in such a manner as to allow the 70 plate *a*, if it is free, to have a movement of a few millimeters above and under the horizontal position of the said elements.

A rigid rod *e* which is convex at its upper part and concave at its lower part, rests 75 on a knife-edge *f* of the Roman balance and supports at *g* the weight of the plate *a*.

The length of this rod is determined in such a manner that, when the indexes *h* *i* are opposite each other, the inner points of 80 attachment of the flexible wires *c* are very slightly above the horizontal plane in which are located the outer attachment members or stretching devices *d* of the cross pieces.

The apparatus being in equilibrium in 85 this position with a mass *j*, if this mass is placed on one of the sides of the plate *a*, as indicated in Fig. 1, the various wires *c* constituting the cross pieces are stretched, but as they are practically horizontal, there 90 does not exist any component capable of introducing a modification in the pressure supported by the knife-edge *f*.

Moreover, as the rod *e* and the knife-edge *f* do not support any lateral stress, the 95 stress transmitted by this knife-edge *f* remains constant whatever may be the position of the mass *j* on the plate *a*.

Figure 3 illustrates the method of suspension applied to a Conti balance. 100

In this case, the plate *a* of the balance is integral with a rigid member *b*¹ held laterally and at both ends by cross pieces constituted, as stated above, by flexible wires *c*.

This member rests on a vertical rod *e* 105 which transmits the weight to the suspension knife-edge *f* of the balance.

The weighing is effected, in this system,

by means of a steel-yard k having a weight k^1 , the knife-edge l of which rests on a support integral with an arm m rocking about an axis substantially coinciding with the 5 peak of the suspension knife-edge f of the balance.

The arm m rests, through a rolling pathway m^1 , on a roller n mounted on a nut o moving on a vertical screw p the number of 10 revolutions of which registered on an indicating dial q gives the weight.

In the two examples illustrated, the balances comprise a single plate which transmits the pressure through a vertical rod to 15 the end of this rod.

When, as in the case illustrated in Figs. 4 and 5, the balance comprises two plates, the vertical rod can be replaced by frames b^2 with knife-edges.

20 In case the first knife-edge thus receiving the load is of great length or composed of two elements widely spaced apart, the vertical rod may be replaced by a frame b^2 supporting a second frame b^3 integral with the 25 plate a , as diagrammatically illustrated in Fig. 5.

In this case, the cross pieces comprise only

two flexible wires c instead of four, as it suffices for the plate to be held on one direction only.

30 The constructional arrangements above described are of course given by way of example only and it is obvious that they can be modified according to the various types of balances without departing thereby from the 35 principle of the invention.

Claim:

In a balance, a balance plate, a suspension device therefor comprising a substantially vertical member extending rigidly from 40 the plate, a knife-edge suspension, a second vertical member supporting the first vertical member and thereby the plate on the knife-edge, and a plurality of flexible inextensible filaments stretched horizontally 45 between fixed points of the balance and the first vertical member in such a manner as to permit only very slight vertical movements of the balance plate and to eliminate lateral pressure on the knife-edge.

50 The foregoing specification of my "suspension for balance plates" signed by me this 14th day of May, 1920.

JAMES TIBURCE FELIX CONTI.
